UNITED STATES PATENT OFFICE.

MICHAEL RUNSTETLER, OF DAYTON, OHIO, ASSIGNOR TO THE FARMERS FRIEND MANUFACTURING COMPANY, OF SAME PLACE.

SEEDING-MACHINE.

SPECIFICATION forming part of Letters Patent No. 240,463, dated April 19, 1881.

Application filed February 1, 1881. (Model.)

To all whom it may concern:

Be it known that I, MICHAEL RUNSTETLER, a citizen of the United States, residing at Dayton, in the county of Montgomery and State of Ohio, have invented certain new and useful Improvements in Seeding-Machines, of which the following is a specification.

My invention relates essentially to improvements in the rotary dropping mechanism of seeding-machines, more particularly to that class known as "corn-planters."

It consists, first, of a reciprocating slide having gravitating pawls arranged upon it within the circle of the seeding-holes of the rotating dropper-plate, in combination with a peculiar-shaped star-wheel rotating in a horizontal plane around and held in position by a stud or pivot on the bed or supporting-plate and connected to the rotating seed-wheel by crank-pins or studs.

My invention consists, in the second part, in the use of lugs upon the reciprocating slide, which, in combination with the gravitating pawls and lugs upon the star-wheel, act as stops to impart positive intermittent motion to the seed-wheel, and the arrangement of these lugs is such as to absolutely prevent the locking of the seeding mechanism.

My invention consists, in the third part, in the provision of a spring cut-off which is arranged above the circular series of seed-holes, and is located in a housing or boxing on the upper plate or cap, in which it works on trunnions in bearings made in the housings, the said cut-off being provided with a shoulder abutting the forward depending wall of the housings, from which point it projects forward and rests upon the seed-plate.

Another feature of my invention consists in the mode of attaching a spiral spring to the upper side of the cut-off, so as to regulate its movements. The object of thus constructing and arranging the cut-off is, first, to prevent dust, chaff, and dirt from coming in contact with the spring, trunnions, and other parts of the cut-off which are on the inside of the housing, and thereby secure an easy and accurate adjustment and operation of the cut-off. To

enable this adjustment to be easily made the cap of the housing is made of peculiar shape, and is held in position by means of a bolt, which secures both the cap and cut-off in position; and, second, the construction and arrangement of the spring cause it to work with great accuracy and durability.

In the accompanying drawings, Figure 1 is a plan view, representing the seed-box of a planter with the upper plate or cap in position. Fig. 2 is a plan view of the dropping device, showing the cap removed, the slide-bar being at the termination of the stroke and ready for the return. Fig. 3 is a plan view of the same, showing the dropper-plate and the stationary plate below it removed, a portion of the slide-bar being broken away. Fig. 4 is a vertical sectional elevation on line *x* *x*, Fig. 1, but showing the feed-box removed. Fig. 5 is a broken longitudinal elevation of one end of the upper plate or cap at which the cut-off and its box are located. Fig. 6 is a longitudinal sectional elevation on line *y* *y* of Fig. 1. Fig. 7 is a plan view of the cut-off. Fig. 8 is a detail perspective view of the device which rotates the dropper-plate, motion being communicated thereto by the pawls on the sliding plate.

A represents an ordinary seed-box or hopper of a corn-planter or seeding-machine. It is constructed with an open bottom for the reception and operation of the dropping mechanism.

B represents the base-plate of the dropping mechanism.

C represents the slide.

C' represents the gravitating pawls, which are hinged between ears which are cast on slide C. These pawls are arched or bent so that they will reach over the lugs *d*, with their front end resting on the plate or slide C.

e represents stops, which are made of the form shown, so that as they approach lug *d* they will not catch upon the point of the lug and lock the device.

D represents the star-wheel.

D' represents crank-pins, which connect the star-wheel with the seeding-wheel F.

d represents the lugs or teeth of the star-wheel.

d' represents the lugs beveled off, the object of which is more readily to raise the pawls as they are alternately lifted by the lugs in their backward movement. These bevels *d'* are not essential, as the pawls *C'* may be bent sufficiently to arch over the lugs *d*.

b' represents elevated ledges projecting upward from the base-plate *B* a sufficient distance, so that the annular ring *E* and the seed-wheel *F* are supported above the pawls *C'*, allowing sufficient vertical space between the plate *E* and reciprocating slide *C* for the pawls *D* to rise and fall as they alternately pass over lugs *d* in the act of intermittently rotating the star-wheel *D*. This space between the parts *E* and *C* is very important, as it allows the gravitating pawls to be brought within the circles of the seed-holes *f*, to alternately engage and pass over the lugs *d*. These gravitating pawls are very positive in their motion, and in order that they may be employed in a corn-planter which uses a check-rowing device it is necessary that they be brought within the circle of the seed-hole *f*, so that a short reciprocating movement of the slide *C* will rotate the seed-wheel, and the shorter the stroke of the slide *C* the easier and more accurate will be the operation of the check-rower. The annular plate *E* is rigidly fastened to ledges *b'* by bolts or rivets *e*.

b'' represents a slot cut in the side of the base *B*, to provide a passage for the seed.

35 The annular plate *E* is made of the usual form, and forms a bed or base for the rotating seed-plate *F*; and the annular plate is cut away to form an opening or passage similar to *b''*, in order to permit the seed to drop as the holes *f* are progressively carried over the opening. The seed-wheel *F* is provided with a central bridge, through which are pierced two holes for the reception of studs *D'* on star-wheel *D*. These holes should rather loosely fit stud-pins *D'*, to prevent the binding of the parts, and yet sufficiently close to obtain a positive uniform motion of the parts *D* and *F*.

G represents the bridge or top plate covering the seeding devices.

50 *g* represents a ledge or lug projecting from the top of the plate in rear of the cut-off.

H' represents projecting flanges, which act as guides, and between which the cut-off *I* rises and falls. It is provided with trunnions *i*, on which it turns.

H represents a cap of peculiar shape, which fits upon the ledges *g* and *H'*, and forms a complete boxing or cover for the rear portion of the cut-off plate *I*.

60 *h'* represents the forward end of this cap, which is brought to a knife-edge at the bottom and closely abuts the shoulder *I'* and makes a close fit, to prevent chaff and dust from working into the parts *h*, *J*, and *I'*. The beveled shape of the part *h'* prevents seed from

being caught between it and the cut-off *I* as it is raised. This feature is important, as otherwise the seed would wedge in and prevent the cut-off *I* from rising.

J represents a coiled spring wound around the stud *h* and resting upon the bottom of the socket cut in boss *I'*. The construction of the parts *h'* and *I'* holds the coiled spring *J* in place and secures the ready movement of the cut-off *I*.

h represents a pin or stud projecting from cap *H* downward into the socket of the boss *I'*.

h'' represents a screw-bolt, which secures the cap *H* to the plate *G*. This form of construction of the cap is quite important, as it allows accurate fitting of the parts *h*, *I*, and *I'*, and securely holds the parts in proper position, making a tight housing for the cut-off pawl *I*, and secures its positive operation. This is a great improvement, as the operation of this cut-off secures a uniform charge in each of the holes *f* as the seed-wheel *F* is rotated.

Having thus described my invention, what I claim is—

1. The combination, with the elevated horizontal seed-wheel and the star-wheel connected therewith, of the reciprocating slide provided with stops *c* and gravitating pawls *C'*, adapted to rise and fall in a vertical plane, and arranged upon the face of the slide to move within the circle of seed-holes in the seed-wheel, substantially as described, for the purposes set forth.

2. The combination, with the horizontal seed-wheel and the wheel *D*, having radial lugs *d*, of the reciprocating slide *C*, having fixed stops *c* and arched gravitating pawls *C'*, pivoted upon the slide and arranged to rise and fall in a vertical plane within the circle of seed-holes in the seed-wheel and to span the lugs *d*, substantially as described.

3. The combination of the base *B*, having vertical ledges *b'*, the annular plate *E*, attached to the upper ends of said ledges, the seed-wheel *F*, arranged above the annular plate, the star-wheel arranged below the annular plate and adjacent to the base, and connected with the seed-wheel by vertical arms or pins, and the reciprocating slide *C*, having stops *c*, and gravitating rising and falling pawls arranged to engage the lugs of the star-wheels, substantially as described.

4. The covering-plate *G*, provided with the upwardly-projecting end lug, *g*, and side flanges, *H'*, in combination with the cap *H*, bearing at one end against the lug *g* and partially inclosing the trunnioned cut-off *I*, the forward end of the latter being guided by the flanges *H'*, substantially as described.

5. The combination, with the trunnioned cut-off *I*, having the vertical boss *I'*, with the fixed cap *H*, having the depending front end, *h'*, provided with a knife-edge closely abutting against the outer edge of boss *I'*, substantially as and for the purpose described.

6. The combination of the trunnioned cut-off I, having the vertical recessed boss I', with the fixed cap H, having the depending stud h and a depending front end, h', and the spring 5 J, encircling the stud on the cap and resting in the recess of the boss, substantially as described.

In testimony whereof I have hereunto set my hand in the presence of two subscribing witnesses.

MICHAEL RUNSTETLER.
